ABRAHAM W. LAIR, OF LOS ANGELES, CALIFORNIA

MASSAGE MACHINE

Application filed January 28, 1927. Serial No. 164,288.

My invention relates to massage machines, and the objects are first, to produce a mechanism whereby all the varied physiological effects for massage are obtained by alternate condensation and rarefaction of air within a cup placed adjacent the human body, the therapeutic value of which lies in the facts that by such mechanical action the circulation of blood is enhanced and stagnation is overcome, capillary stasis is freed and excessive labor is removed from the heart, the lymphatic glands and vessels are also stimulated to better action thus causing broken down cells and waste matter to be removed from the blood plasma, hence the blood is purified, and in turn the nervous system receives blood of a better quality and is brought into a normal and healthy activity; second, to produce a mechanism that relieves inflammation and promotes the absorption of abnormal deposits in the tissues by reason of its power to induce hyperemia and diapedesis; third, to raise a subnormal temperature and induce a normal healthy metabolism, and to help the leucocytes to combat invading bacteria and lessen the tendency to infections.

Another valuable feature of the invention is its utility as a massage machine adapted for exercising or massaging pneumatically the tympanum in the treatment of certain diseases and abnormal conditions of the ear.

A further object of the invention is to provide a simple, durable and efficient device for the accomplishment of the above mentioned purposes, as well as other purposes which will become apparent from a perusal of the following specification, and an examination of the accompanying drawings, in which:

Figure 1 represents a perspective outside view of my massage machine, with the cabinet in open position.

Figure 2 represents a sectional view taken on line 2—2 of Figure 1.

Figure 3 represents a sectional view taken on line 3—3 of Figure 5, showing the tube and body connector attached and in part section.

Figure 4 represents an enlarged frag-

mental view of the crank means for my machine, shown in Figure 1.

Figure 5 represents a sectional view taken on line 5—5 of Figure 3.

Figure 6 represents a sectional view taken on line 6—6 of Figure 7.

Figure 7 represents sectional view taken on line 7—7 of Figure 1.

Figure 8 is a fragmental plan view on line 8—8 of the valve control means shown in Figure 7.

Figure 9 is a plan view of valve levers shown in Figure 7.

Figure 10 is another plan view of valve levers shown in Figure 7.

Figure 11 is a plan view of the adapter shown in Figure 1.

My invention comprises a cabinet 1, in which is placed a motor 2 mounted upon a suitable base 3, the base 3 is in turn slidably held in position in the guides 4, and adjustably clamped into position by the screws 5. The motor 2 being connected to a shaft 6 with pulleys 7 and 8 mounted on the shaft 6, and motor 2, respectively. The shaft 6 is journaled in bearings 9 and supports a crank 10 on the outer end thereof, two lugs 11 are in turn formed opposite one another on the center line of the crank 10, two slides 12 are secured between the lugs 11, spaced equidistant from the said center line of the crank 10, and a screw 13 is turnably mounted on the center line of the crank 10, in the lugs 11. A block 14 is slidably mounted upon the slides 12, and adjustably supported by the screw 13. The center of the outer end of the block 14 is formed with a pin 15, and one end of a connecting rod 16 is operatively secured thereon.

A pump 17 is secured in the cabinet 1 with relation to the said crank 10 having pump heads 23 secured in both ends of the barrel thereof, and a shaft 18 passes slidably through the longitudinal center of the pump barrel within bearings 19, and the pump heads 23 are secured in both ends of the barrel of said pump 17. A piston 20 is slidably secured on the shaft 18 in the said pump, one end of said shaft 18 being formed

with a joint 21, and the joint 21 is in turn connected to the connecting rod 16.

The pump head 23 is formed with two valves 22, one being positioned at each end thereof, as shown in Figure 7. Slide members 24 are operatively positioned over said valves 22, and are opened and closed by links 25, the links 25 being operated by the levers 26. The levers 26 are adjustably mounted on the fulcrum members 27, and the lugs 28 are formed on the outer ends thereof with relation to graduated slots 29 in a plate 30, the plate 30 being secured upon a support in said cabinet 1. The valves 31 are also positioned in the two ends of the pump heads 23, as shown in Figure 7 and the flapper members 32 are hingedly secured to the said heads 23. The shafts 33 are operatively mounted in bearings 35, said bearings being formed on the heads 23, and the cams 34 are in turn formed on the lower ends of said shafts 33, and levers 36 are secured to the upper ends thereof. Plates 37 with arcuate flanges 40 formed about center of the shafts 33 are secured to the cabinet 1 with relation to said levers 36, graduated notches 39 being formed in the outer arcuate flange 40, and lugs 38 are in turn formed on the said levers 36 to engage with said notches 39.

The adapter 41 comprises a bore 42 in which is slidably mounted a sleeve 43, and a head 44 is in turn permanently secured in the sleeve 43, the screw 45 being arranged to clamp said sleeve 43 stationary within said bore 42 when desired.

The heads 57 are secured in both ends of the bore 42 and the screws 53 and 54 are in turn adjustably clamped in their respective heads 57, with bumper ends 58 and 59 secured to the inner ends of the said screws 53 and 54, respectively, within the sleeve 43, facing the said head 44. Both ends of the bore 42 open into passages 50 and 51 respectively, and a passage 52 is formed to open into the center portion of the bore 42 through ports 48 and 49. The sleeve 43 is formed with ports 46 and 47 spaced from one another to alternately open and close the ports 48 and 49 respectively, as the said sleeve 43 and head 44 reciprocate back and forth between the bumpers 58 and 59, with a predetermined stroke, depending upon the position of the said screws 53-54 and head 44 within the sleeve 43. Oil cups 55 are secured in the upper portion of the adapter 41 to supply oil to the bearing surface between the bore 42 and sleeve 43 and the overflow oil therefrom accumulating in the passage 52 may be drained through a petcock 56 positioned in the bottom wall thereof.

The pipes 68 and 69 are connected between the chambers 70 and 71 respectively, in the pump 17, and the passages 51 and 50 respectively, in the adapter 41, connectors 72 and 73 are formed in the passage 52 and pipe 69

respectively, to detachably hold a hose 60, the opposite end of the hose 60 being secured to a housing 62 and cup 61, the housing being provided with flapper valves 63 and 64, and control arms 65 and 66 respectively.

Before operating my invention the position of the motor 2 is adjusted to regulate the distance between the pulleys 7 and 8 to give a tight gripping or loose sliding belt connection 74, by sliding the base 3 in the guides and clamping the screws 5 in positions so that the pin 77 will read where required on the scale 76. The stroke of the connecting rod 16 is adjusted by setting the block 14 on the slides 12 a distance from the dead center of the crank 10, to read where required on the scale 75, by turning the screw 13, thus determining the length of the strokes of the piston 20 in the pump 17. The openings in the valves 22 are adjusted by placing the slide members 24 thereover, by placing the lugs 28 in the required slots 29 thus holding the connecting levers 26 and links 25 in stationary positions.

The openings in the valves 31 are adjusted to open and close alternately by the flappers 32, said flappers being controlled as required by the cams 34 which are swung about on the center of the shafts 33 with relation to the position of the levers 36, the lugs 38 being set into the adjacent graduated notch 39.

When the two valves at each end of the pump 17 are both adjusted to maintain them in the closed position and the adapter sleeve 43 is held stationary by the rods 53 and 54 (Figure 5) being adjusted to hold the heads 58 and 59 against opposite sides of head 44, then an equal and too forcible puff and suction will be applied to the surface of the body by the applicator cup 61. The various adjustments of valves and of the length of the stroke of the adapter head 44 are provided to soften such action and to regulate amount of puff as compared with suction. The valves at each end of pump 17 will, in proportion to the extent which they permit air to enter and to leave the pump, weaken the reciprocatory force applied to the adapter, but if these valves are symmetrically adjusted, puff and suction will be equal.

The position and stroke of the sleeve in the bore 42 is adjusted where required by first clamping the said sleeve 43 to read on the scale 78, and then adjusting the screw ends 58 and 59 to predetermined distances from the center of said bore 42 to control the openings between the ports 47-49 and 46-48.

The operation will be more readily understood if it is borne in mind that the electric motor 2 is operatively connected with the pump piston 20 in such a manner as to reciprocate said piston quite rapidly, and the cross-sectional area of the piston cylinder 17 is more than twice that of the space inclosed by the sleeve 43 of the adapter, thus provid-

ing for transmission to said sleeve 43 of about double the amount of movement for each reciprocation which is being given at any time to the piston 20, providing the valve closures 24 of the pump cylinder heads 23 are adjusted to the completely closed position. That is to say, while the pump piston moves one inch the sleeve of the adapter will move about two inches. The extent to which the flapper valves 31 open may also be regulated as desired, but the opening of the valves 31 does not interfere with movement, by suction, being transmitted from the piston cylinder 17 to the sleeve 43. There is continuous communication (see Figures 5, 6 and 7) between chambers 50 and 71 and between chambers 51 and 70 hence, since the pump piston 20 reciprocates rapidly and as the area thereof is more than twice the area inclosed by the sleeve 43, considerable leakage may be permitted thru the valve openings 22 without rendering ineffective the action of the sleeve 43 in transmitting the desired variations of atmospheric pressure to the applicator cup 61.

With the several adjustments made as to the position of the motor 2, crank 10, valves 22, valves 31, head 44 and bumper ends 58-59, power is transmitted from the motor 2 through the pulley 8, belt 74, pulley 7, shaft 6 and crank 10 respectively. The turning movement of the crank 10 forces the piston 20 in the pump 17 to reciprocate through the shaft 18, and the connecting rod 16 connected thereto.

Pipe 68 leads to cylinder chamber 70 at the right of piston head 20 as viewed in Figures 1, 2 and 6, and pipe 69 leads to the other cylinder chamber 71. Now when piston rod 18 moves to the left (cams 34 holding closed flappers 32, both ends of cylinder) the air is sucked from chamber 51, Figure 5, and the suction draws sleeve 43 toward the left end of chamber 42, until partition 44 strikes the bumper 59. At the same time this suction action is taking place in the right end of the cylinder 17 and left end of the adapter there is also a compression action in the left end of said cylinder and right end of the adapter as follows: Piston head 20 moving to the left creates a pressure in chamber 71 of pump cylinder 17. This pressure is conducted through pipe 69 to chamber 50, from where it forces sleeve 43 toward the left. Hence on one side of partition 44 there is suction isochronously with a compression on the other side, thus operating the sleeve.

The housing 62 is provided to afford a means whereby, without changing the action of the machine, a continuous suction, a continuous blowing or an alternating suction and blowing effect may be obtained merely by operating the valves 63-64 by the controls 65-66 respectively with the cup 61 on the body. The mode of pneumatic delivery

can be changed instantly through said valves 63-64 without changing the setting of the machine in general. The valves can also be permanently set in the adapter 41 for any mode of pneumatic delivery when using various sized cups 61.

The stroke of the crank 10 is lengthened or shortened when changing from a small cup 61 to a larger cup 61, to provide the necessary pneumatic volume.

Having thus described my invention what I claim is:

1. In a massage machine, a double acting pneumatic pump adapted to give puff or suction strokes, an operating means for said pump, a double acting adapter comprising a reciprocating sleeve and having passages connected to respective chambers in said pump and controlled by said sleeve, a regulating means connected to said pump to control the puff or suction strokes therefrom, a regulating means connected to said adapter to control the delivery of puff or suction strokes therefrom, and a delivery means connected to said adapter to be applied to the surface of the human body.

2. In a massage machine, an adjustable acting pneumatic puff or suction pump, an adjustable operating means connected to said pump adapted to control the puff or suction strokes of said pump, a power means connected to said adjustable operating means, an adjustable double acting adapter having an air passage connected to respective chambers in said pump, and a controllable delivery means comprising ports and connected to said adapter applicable to the human body, said adapter comprising an adjustable piston element operable by said pump and controlling said ports.

3. In a massage machine, an adjustable acting pneumatic puff or suction pump, an adjustable operating means connected to said pump adapted to control the puff or suction strokes of said pump, a power means connected to said adjustable operating means, an adjustable double acting adapter having an air passage connected to respective chambers in said pump, said adapter having a piston element reciprocated by said pump to control said passage, and a controllable delivery means connected to said adapter applicable to the human body, auxiliary air connection in the passages connected between the said pump and adapter, an auxiliary controllable delivery means adapted to be connected to said auxiliary air connection.

4. A massage machine including a puff and suction pump, operating means for said pump, an adapter including a casing formed with a bore, a pair of passages communicating with the ends respectively of said bore, a third passage provided with two ports, a sleeve slidable in said bore and provided

- with two ports adapted respectively to register with said ports of said third passage when the sleeve is at one end or the other of its stroke, a head secured within said sleeve, set screws seated in said casing and extending into opposite ends respectively of said sleeve for respectively engaging said head, for limiting the movement of said piston, said pair of passages being respectively connected to the ends respectively of said pump, and delivery means connected to said third passage to be applied to the human body.
5. A massage machine including a puff and suction pump, each head of said pump being formed with two valves, a closure member for one of said valves, means for regulating said closure member, a flapper member for the other valve, means for regulating said flapper member, operating means for said pump, an adapter connected to said pump to regulate the flow and pressure of pneumatic puff and suction from said pump, and a delivery means connected to said adapter to be applied to the human body, said adapter comprising a piston element one side of which is acted upon by the puff from said pump while the other side is simultaneously acted upon by suction therefrom.
6. A massage machine including a pneumatic puff and suction pump, operating means for said pump, an adapter connected to said pump to regulate the flow and pressure of pneumatic puff and suction from said pump, and delivery means including a tube and a cup connected to said tube and a pair of valves within the passage leading into said cup to vary the size of said passage thereby regulating the puff and suction respectively within said cup.
7. A massage machine including a pneumatic puff and suction pump, operating means for said pump, an adapter connected to said pump to regulate the flow and pressure of pneumatic puff and suction from said pump, said adapter comprising a piston element and air ports controlled thereby, each side of said piston element being alternately acted upon by the puff and the suction from said pump, there being air ports controlled by said piston element, and delivery means communicating with said ports and applicable to the human body.
- 55 In testimony whereof I hereunto affix my signature.

ABRAHAM W. LAIR.
